UNITED STATES PATENT OFFICE.

HERMAN C. PRIEBE, OF BLUE ISLAND, ILLINOIS.

DRAFT GEAR.

Application filed March 20, 1922. Serial No. 545,101.

To all whom it may concern:

Be it known that I, HERMAN C. PRIEBE, citizen of the United States, residing at Blue Island, in the county of Cook and State of Illinois, have invented a certain new and useful Improvement in Draft Gears, of which the following is a full, clear, concise, and exact description.

My invention relates to railway cars and particularly to the underlying structures thereof, and has for its general object the provision of improved means for effecting the assembly of draft gears with the balance of the cars.

In accordance with my invention the inner or so-called rear draft lugs with which the inner portions of the draft gears are in abutting relation are not only mounted upon draft arms but, in addition, are reinforced by the adjacent body bolsters to avoid or reduce the shearing action upon the rivets which hold these lugs in place.

My invention is of particular service in connection with freight cars that employ underlying wooden center sills in pairs. At each end of a car having such sills I provide two angle irons having inner upright sides and lower outwardly extending horizontal sides, each sill having an angle iron individual thereto and received in the angular seat formed by the angle iron. I also provide two horizontal upright draft arms, each angle iron having a draft arm individual thereto and below the same, the lower horizontal side of each angle iron being riveted to its draft arm. The inner draft lugs hitherto referred to have their upright sides riveted to the draft arms and in addition to these upright sides the draft lugs have inwardly extending top sides which are also riveted to the lower horizontal sides of the contiguous angle irons. By means of this construction the draft lugs, in addition to performing their usual function, also serve greatly to strengthen the assembled angle irons and draft arms and to maintain the fixed relation thereof while undergoing severe draft strains. This feature of my invention is highly useful and is believed to be novel whether the inner draft lugs are reinforced by the body bolster or not, and while I have employed this formation in connection with the inner draft lugs, the invention is not to be thus limited.

The top sides of the inner draft lugs are preferably also employed for effecting the

reinforcing relation of the adjacent body bolster with these lugs and to this end these top lug sides are themselves desirably provided with lug formations which engage the front side of a U-shaped or other suitably shaped member that is secured to the angle irons, the rear or inner side of this member engaging the outer upright face of the bolster.

The invention will be more fully explained by reference to the accompanying drawings in which Fig. 1 is a top view showing parts in section and parts in plan of the under structure of a car equipped in accordance with the preferred embodiment of the invention; Fig. 2 is a sectional view on line 2-2 of Fig. 1 with the draft gear shown in dotted lines; Fig. 3 is a sectional view on line 3-3 of Fig. 2; Fig. 4 is a perspective view illustrating some of the component parts of the underlying car structure; Fig. 5 is a perspective view of the inner draft lug; and Fig. 6 is a view, somewhat diagrammatic, illustrating the draft gears at both ends of the car structure and some of the associate parts, the intermediate portion of the car structure being broken away for lack of space.

Like parts are indicated by similar characters of reference throughout the different figures.

The car body is not illustrated as its presence is understood. As the invention is illustrated, it is provided with two longitudinal wooden center sills 1 and 2. There are two angle irons having inner upright sides 3 and lower and outwardly extending horizontal sides 4, each sill having an angle iron individual thereto and received in the angular seat formed by its angle iron. There are two draft arms or draft sills 5 and 6, each angle iron having a draft arm individual thereto and below the same. Each draft arm is preferably in the form of an upright channel iron whose horizontal flanges extend outwardly, the lower horizontal side of each angle iron being riveted to the top flange of its draft arm.

Any suitable form of draft gear is assembled with the draft arm. The gear illustrated includes a coupler 7 and a coupler yoke 8 assembled therewith. The coupler is supported by a key 9 passing therethrough and through elongated slots in the draft arms 5, 6 and also in the front or outer draft lugs 10. The yoke is supported upon a plate

11 bolted to and beneath the bottom flanges of the draft arms. The draft gear illustrated is provided with an outer follower 12 and an inner follower 13, these followers being 5 illustrated in the form of barrels containing springs or other motion resisting mechanism, a spring 14 being illustrated as entering the barrels. Outward movement of the coupler is opposed by the motion resisting 10 mechanism due to the engagement of the outer follower 12 with the outer draft lugs 10. Inward movement of the coupler is opposed by the motion resisting mechanism 15 due to the engagement of the inner follower 13 with the rear or inner draft lugs 15, these latter lugs preferably including all of the novel characteristics which are embraced 20 within the formation of draft lugs in accordance with my invention, although the invention is not to be thus restricted.

These inner lugs have upright sides and inwardly extending top sides, each draft arm having a draft lug individual thereto, the upright side of each draft lug being riveted 25 to the upright side of its draft arm. The top side of each draft lug is riveted to the lower horizontal side 4 of the contiguous angle iron. By thus forming and riveting the inner draft lugs the union or assembly 30 of the draft arms with the angle irons and the wooden center sills is greatly strengthened and relative distorting movements of these parts are, thereby, further resisted.

There is a body bolster 16 at each end of 35 the car, these body bolsters being disposed between and spaced apart from the inner draft lugs. I cause these body bolsters to supplement the inner draft lugs in resisting the inward movements of the draft gears.

40 To this end the top sides of the inner draft lugs themselves are provided with inwardly extending lug formations 17 that are provided for the purpose of engaging a distance piece 18 which is carried by the draft arms 45 and whose outer side is in abutting engagement with the lugs 17 and whose inner side is in abutting engagement with the adjacent body bolster 16.

The distance piece 18 is preferably the 50 base portion of a U-shaped member having upwardly extending sides that are riveted to the upright sides 3 of the aforesaid angle irons. I desirably provide additional angle irons 19 having upright sides against the 55 upright sides of the first aforesaid angle irons and between the same and the upright arms of the distance piece 18. The remaining sides of said additional angle irons are desirably at the top and extend inwardly 60 and horizontally. When the inner lugs are thus associated with the body bolsters adjacent thereto the shearing strains upon the rivets that hold these lugs in place is effectively counteracted.

65 Each car that is constructed in accordance

with my invention has, at each of its ends, the inner draft lugs 15 and the parts associated and assembled therewith as will be understood by those skilled in the art and as somewhat diagrammatically illustrated in 70 Fig. 6.

While I have herein shown and particularly described the preferred embodiment of my invention I do not wish to be limited to the precise details of construction shown as 75 changes may readily be made without departing from the spirit of my invention, but having thus described my invention I claim as new and desire to secure by Letters Patent the following:—

1. A car structure including two longitudinal wooden center sills; two angle irons having inner upright sides and lower outwardly extending horizontal sides, each sill having an angle iron individual thereto and received in the angular seat formed by its angle iron; two draft arms in the form of longitudinal upright channel irons whose horizontal flanges extend outwardly, each angle iron having a draft arm individual thereto and below the same, the lower horizontal side of each angle iron being riveted to the top flange of its draft arm; two inner draft lugs having upright sides and inwardly extending top sides, each draft arm having a draft lug individual thereto, the upright side of each draft lug being riveted to the upright side of its draft arm; a bolster underlying the wooden center sills and extending transversely thereof; additional angle irons having upright sides against the upright sides of the first aforesaid angle iron and upper inwardly extending horizontal sides; a U-shaped member extending between the upright sides of the additional angle irons and having upwardly extending sides each riveted to the upright sides of both angle irons adjacent thereto, the inner side of the base of said U-shaped member engaging the outer upright face of said bolster, the top sides of the draft lugs themselves having inwardly extending lug formations that engage the outer side of the base of the U-shaped member; and a draft gear assembled with said draft arms and having a portion in abutting relation to the outer ends of said draft lugs.

2. A car structure including two longitudinal wooden center sills; two angle irons having inner upright sides and lower outwardly extending horizontal sides, each sill having an angle iron individual thereto and received in the angular seat formed by its angle iron; two draft arms in the form of longitudinal upright channel irons whose horizontal flanges extend outwardly, each angle iron having a draft arm individual thereto and below the same, the lower horizontal side of each angle iron being riveted to the top flange of its draft arm; two inner

draft lugs having upright sides and inwardly extending top sides, each draft arm having a draft lug individual thereto, the upright side of each draft lug being riveted to the upright side of its draft arm; a bolster underlying the wooden center sills and extending transversely thereof; a U-shaped member extending between the angle irons and having upwardly extending upright sides each riveted to the adjacent upright angle iron side, the inner side of the base of said U-shaped member engaging the outer upright face of said bolster, the top sides of the draft lugs themselves having inwardly extending lug formations that engage the outer side of the base of the U-shaped member; and a draft gear assembled with said draft arms and having a portion in abutting relation to the outer ends of said draft lugs.

3. A car structure including two longitudinal wooden center sills; two angle irons having inner upright sides and lower outwardly extending horizontal sides, each sill having an angle iron individual thereto and received in the angular seat formed by its angle iron; two draft arms in the form of longitudinal upright channel irons whose horizontal flanges extend outwardly, each angle iron having a draft arm individual thereto and below the same, the lower horizontal side of each angle iron being riveted to the top flange of its draft arm; two inner draft lugs having upright sides and inwardly extending top sides, each draft arm having a draft lug individual thereto, the upright side of each draft lug being riveted to the upright side of its draft arm; a bolster underlying the wooden center sills and extending transversely thereof; additional angle irons having upright sides against the upright sides of the first aforesaid angle iron and upper inwardly extending horizontal sides; an abutment structure riveted to the upright sides of the angle irons and engaging the outer upright face of said bolster, the top sides of the draft lugs themselves having inwardly extending lug formations that engage said abutment structure which is interposed between said lug formations and the bolster; and a draft gear assembled with said draft arms and having a portion in abutting relation to the outer ends of said draft lugs.

5. A car structure including two longitudinal wooden center sills; two angle irons having inner upright sides and lower outwardly extending horizontal sides, each sill having an angle iron individual thereto and received in the angular seat formed by its angle iron; two longitudinal draft arms, each angle iron having a draft arm individual thereto and below the same, the lower horizontal side of each angle iron being riveted to its draft arm; two inner draft

lugs having upright sides and inwardly extending top sides, each draft arm having a draft lug individual thereto, the upright side of each draft lug being riveted to its draft arm; a bolster underlying the wooden center sills and extending transversely thereof; additional angle irons having upright sides against the upright sides of the first aforesaid angle iron and upper inwardly extending horizontal sides; a U-shaped member extending between the upright sides of the additional angle irons and having upwardly extending sides each riveted to the upright sides of both angle irons adjacent thereto, the inner side of the base of said U-shaped member engaging the outer upright face of said bolster, the top sides of the draft lugs themselves having inwardly extending lug formations that engage the outer side of the base of the U-shaped member; and a draft gear assembled with said draft arms and having a portion in abutting relation to the outer ends of said draft lugs.

5. A car structure including two longitudinal wooden center sills; two angle irons having inner upright sides and lower outwardly extending horizontal sides, each sill having an angle iron individual thereto and received in the angular seat formed by its angle iron; two longitudinal draft arms, each angle iron having a draft arm individual thereto and below the same, the lower horizontal side of each angle iron being riveted to its draft arm; two inner draft lugs having upright sides and inwardly extending top sides, each draft arm having a draft lug individual thereto, the upright side of each draft lug being riveted to its draft arm; a bolster underlying the wooden center sills and extending transversely thereof; additional angle irons having upright sides against the upright sides of the first aforesaid angle iron and upper inwardly extending horizontal sides; an abutment structure riveted to the upright sides of the four angle irons and engaging the outer upright face of said bolster, the top sides of the draft lugs themselves having inwardly extending lug formations that engage said abutment structure which is interposed between said lug formations and the bolster; and a draft gear assembled with said draft arms and having a portion in abutting relation to the outer ends of said draft lugs.

6. A car structure including two longitudinal wooden center sills; two angle irons having inner upright sides and lower outwardly extending horizontal sides, each sill having an angle iron individual thereto and received in the angular seat formed by its angle iron; two longitudinal draft arms, each angle iron having a draft arm individual thereto and below the same, the lower horizontal side of each angle iron being riveted to its draft arm; two inner draft

lugs having upright sides and inwardly extending top sides, each draft arm having a draft lug individual thereto, the upright side of each draft lug being riveted to its draft arm; a bolster underlying the wooden center sills and extending transversely thereof; a U shaped member extending between the angle irons and having upwardly extending upright sides each riveted 10 to the adjacent upright angle iron side, the inner side of the base of said U-shaped member engaging the outer upright face of said bolster, the top sides of the draft lugs themselves having inwardly extending lug formations that engage the outer side of the base of the U-shaped member; and a draft gear assembled with said draft arms and having a portion in abutting relation to the outer ends of said draft lugs.

20 7. A car structure including two longitudinal wooden center sills; two angle irons having inner upright sides and lower outwardly extending horizontal sides, each sill having an angle iron individual thereto and 25 received in the angular seat formed by its angle iron; two longitudinal draft arms, each angle iron having a draft arm indi-

vidual thereto and below the same, the lower horizontal side of each angle iron being riveted to its draft arm; two inner draft lugs having upright sides and inwardly extending top sides, each draft arm having a draft lug individual thereto, the upright side of each draft lug being riveted to its draft arm; a bolster underlying the wooden center sills and extending transversely thereof; additional angle irons having upright sides against the upright sides of the first aforesaid angle iron and upper inwardly extending horizontal sides; an abutment 30 structure riveted to the upright sides of the angle irons and engaging the outer upright face of said bolster, the top sides of the draft lugs themselves having inwardly extending lug formations that engage said 35 abutment structure which is interposed between said lug formations and the bolster; and a draft gear assembled with said draft arms and having a portion in abutting relation to the outer ends of said draft lugs. 40

In witness whereof, I hereunto subscribe my name this 13th day of March, A. D. 1922.

HERMAN C. PRIERE.
